(57) **CLAIM**

The ornamental design for an RTU IO module with expansion end plate, as shown and described.

DESCRIPTION

FIG. 1 is a top plan view of an RTU IO module with expansion end plate;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof;

FIG. 7 is a top right front perspective view thereof; and,

FIG. 8 is a top left front perspective view thereof.

The broken line showing of RTU IO module with expansion end plate is for illustrative purposes only and forms no part of the claimed design.
